DISTILLATION AND STABILIZATION PROCESS

Filed June 3, 1939

2 Sheets-Sheet 1

Fig. 1.

<img alt="A detailed process flow diagram for a petrochemical plant. The diagram shows the flow of hydrocarbons from various storage tanks and columns through a series of heat exchangers, condensers, and pumps. Key components include: Propane Storage tanks (92), Butane Storage tanks (91), No. 1 Column (38), No. 2 Column (62), Preheater (12), Preheater (14), Coolers (16, 18, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 309, 310, 311, 312, 313, 314, 315, 316, 317, 318, 319, 319, 320, 321, 322, 323, 324, 325, 326, 327, 328, 329, 329, 330, 331, 332, 333, 334, 335, 336, 337, 338, 339, 339, 340, 341, 342, 343, 344, 345, 346, 347, 348, 349, 349, 350, 351, 352, 353, 354, 355, 356, 357, 358, 359, 359, 360, 361, 362, 363, 364, 365, 366, 367, 368, 369, 369, 370, 371, 372, 373, 374, 375, 376, 377, 378, 379, 379, 380, 381, 382, 383, 384, 385, 386, 387, 388, 389, 389, 390, 391, 392, 393, 394, 395, 396, 397, 398, 399, 399, 400, 401, 402, 403, 404, 405, 406, 407, 408, 409, 409, 410, 411, 412, 413, 414, 415, 416, 417, 418, 419, 419, 420, 421, 422, 423, 424, 425, 426, 427, 428, 429, 429, 430, 431, 432, 433, 434, 435, 436, 437, 438, 439, 439, 440, 441, 442, 443, 444, 445, 446, 447, 448, 449, 449, 450, 451, 452, 453, 454, 455, 456, 457, 458, 459, 459, 460, 461, 462, 463, 464, 465, 466, 467, 468, 469, 469, 470, 471, 472, 473, 474, 475, 476, 477, 478, 479, 479, 480, 481, 482, 483, 484, 485, 486, 487, 488, 489, 489, 490, 491, 492, 493, 494, 495, 496, 497, 498, 499, 499, 500, 501, 502, 503, 504, 505, 506, 507, 508, 509, 509, 510, 511, 512, 513, 514, 515, 516, 517, 518, 519, 519, 520, 521, 522, 523, 524, 525, 526, 527, 528, 529, 529, 530, 531, 532, 533, 534, 535, 536, 537, 538, 539, 539, 540, 541, 542, 543, 544, 545, 546, 547, 548, 549, 549, 550, 551, 552, 553, 554, 555, 556, 557, 558, 559, 559, 560, 561, 562, 563, 564, 565, 566, 567, 568, 569, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1419, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1519, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1619, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1719, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1819, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1919, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, DISTILLATION AND STABILIZATION
PROCESS

David G. Brandt, Westfield, N. J., assignor to
Power Patents Company, Hillside, N. J., a cor-
poration of Maine

Application June 3, 1939, Serial No. 277,208

18 Claims. (Cl. 196—11)

This invention relates to distillation and stabilization processes for handling hydrocarbon mixtures. More particularly the invention relates to stabilization of gasoline to eliminate undesirable low boiling constituents and to produce a motor fuel product having a desired predetermined boiling range or vapor pressure.

This application is a continuation-in-part of the applicant's pending applications Serial No. 548,062, filed July 1st, 1931, and Serial No. 195,681, filed March 14th, 1938. The subject-matter disclosed and claimed in these applications will be referred to more in detail hereinafter in describing the apparatus shown in the drawings.

Application Serial No. 195,681, was filed as a continuation-in-part of applications Serial Nos. 548,062; 624,979 and 720,539.

This application is also a continuation-in-part of the applicant's prior pending application Serial No. 624,979, filed July 27, 1932, for improvements in "Cracking of petroleum oil," now Patent No. 2,111,354, granted March 15th, 1938. This application discloses a process for condensing and stabilizing the hot vapors removed from a

dephlegmator of a cracking unit by passing all or a part of them in indirect heat exchange with a body of condensate in the bottom of a stabilizer to heat and vaporize condensate of the body, after which all of the vapors are passed through a heat exchanger and a condenser to cool and condense the gasoline constituents and certain of the lower boiling hydrocarbons. The condensate and uncondensed gases are conducted to a receiver in which the condensate is separated

from uncondensed gases and from which it is pumped in indirect heat exchange with the vapors in the heat exchanger to heat it, after which it is introduced into the mid-portion of the stabilizing tower. A pressure of from 250 to 300

pounds per square inch, derived from the cracking unit proper, is disclosed as being maintained in the condensate receiver. Provision is made for condensing overhead vapors from the stabilizer and returning a portion of the resulting condensate to the upper part of the stabilizer as a refluxing medium to maintain the desired temperature at the top of the stabilizer tower.

The present application is also a continuation-in-part of applicant's pending application Serial No. 720,539, filed April 14th, 1934, for improvements in "Method of processing crude petroleum." This pending application discloses a process in which the stream of the pressure distillate vapors produced in the cracking operation disclosed therein, is passed from a high pressure

dephlegmator at a pressure of from 100 to 250 pounds per square inch, and all or a portion thereof passed in indirect heat exchange with a body of liquid gasoline in the bottom of a first stabilizer tower section to heat the gasoline. Subsequently all or a portion of the whole vapor stream from the high pressure dephlegmator is passed in indirect heat exchange with a body of liquid gasoline in the bottom of a second stabilizer tower section to heat this second body of gasoline, after which all of the constituents removed from the high pressure tower are conducted through a heat exchanger and a condenser to cool and condense the gasoline constituents and certain of the lower boiling hydrocarbons contained in the vapors. The resulting condensate and uncondensed gases are conducted into a receiver from which the uncondensed, relatively "dry" gases are removed from a line provided with an automatic pressure controlled release valve.

In accordance with this 1934 application, the condensate collected in the receiver is conducted through a float valve controlled line and passed in indirect heat exchange with the vapors in the heat exchanger in order to heat the condensate, after which it is introduced into the mid-portion of the first stabilizer tower section. The pressure distillate introduced into the first stabilizer section is rectified under conditions adapted to remove the low boiling point constituents such as propane and a part of the butane as vapors, which are subjected to condensation to produce an overhead condensate which is used as overhead reflux to control the temperature at the top of the stabilizer tower section. The gas remaining uncondensed from this overhead condensing operation is removed from a separator-receiver through an automatic pressure regulated relief line. The stabilizer gasoline recovered in the bottom of the first stabilizer tower section is conducted at lower pressure into the mid-portion of the second stabilizer tower section wherein the light gasline constituents are vaporized and separated from the heavier portions of the gasoline by fractionation. The light gasoline constituents are removed as vapors from the second stabilizer tower section through a pressure controlled vapor line, condensed and collected in a receiver. Portions of this light gasoline condensate are pumped respectively, into the upper part of the second stabilizer tower section to control the top temperature therein, and into the upper mid-portion of the first stabilizer tower section above the point of introduction of the

pressure distillate, to aid in controlling the fractionation therein. The heavy gasoline collected in the bottom of the second stabilizer tower section is removed through a float valve controlled line, cooled and refined separate from the light gasoline fraction taken overhead from the second stabilizer section. This pending application discloses the condensation of the pressure distillate and the fractionation thereof in the stabilizer tower sections at pressures of from 100 to 250 pounds per square inch which are derived from the pressures in the cracking unit proper. The use of these pressures aids in the condensation of lower boiling constituents such as propane and butane along with the pressure distillate, and also aids in the fractionation in the first stabilizer tower section.

The primary object of the present invention is the provision of an improved process for recovering and condensing mixtures of hydrocarbon vapors such as pressure distillates, natural and straight run gasolines, desirable hydrocarbon gases, and the stabilization of the resulting condensates or mixtures under conditions adapted to separate lower boiling point constituents and provide products of predetermined boiling range. The process of the present invention is in certain respects an improvement over certain features of the process of the Behimer Patent No. 1,874,860.

In general, the present invention relates to the production of rectified products such as stabilized gasolines or motor fuel having a predetermined vapor pressure or boiling range from materials such as those described above. In accordance with one form of the invention, the steps of the improved process include the passage of the hydrocarbon mixture to be treated in vapor or gaseous form through a heat exchange zone in indirect heat exchange with a condensate produced in the process, the substantially complete condensation of the readily condensable constituents under a relatively high pressure so that substantially only the relatively dry gases remain uncondensed, the collection of the resulting condensate and its separation from the uncondensed gases, the passage of the collected condensate through the heat exchange zone referred to, and the introduction of the resulting heated condensate into a fractionating or stabilizing column wherein the condensate is rectified to remove overhead undesired volatile constituents.

In the modified form of the improved process the steps include the cooling and condensation of the vapor mixture being treated to produce a condensate which is subjected to rectification in a stabilizer tower. In this condensation operation the cooling and condensation is effected by passing the vapors or a portion thereof in indirect heat exchange with the rectified product in the base of the stabilizer tower, then through a heat exchanger and a condenser. The condensate resulting from these cooling steps, or a portion thereof, is conducted in indirect heat exchange with the vapors in the heat exchanger, mixed with another portion thereof (if any) not passed through the heat exchanger, and the total mixture conducted into the stabilizing tower.

The present invention also involves other features including certain automatic control steps which have been found to materially aid in carrying out the process. Those skilled in the art will also appreciate the presence of addi-

tional advantages and features from a consideration of the following more detailed description of the invention taken in connection with the accompanying drawings in which:

Fig. 1 illustrates somewhat diagrammatically an apparatus adapted for carrying out one form of the improved process of the present invention. The apparatus shown in Fig. 1 is the same as that shown and described in applicant's application Serial No. 548,062.

Fig. 2 is a more or less diagrammatic vertical view showing arrangement of apparatus elements particularly adapted for carrying out a modified form of the improved process of the present invention. The apparatus as shown in this figure is the same as that shown and described in applicant's pending application Serial No. 195,681.

In Fig. 1 of the drawings (as described in application Serial No. 548,062), conduit 10 is a line for conducting vapors and fixed gases from a cracking still dephlegmator into one of a series of heat exchangers 12, 14. A valved outlet line 16 for the mixed condensate and gas connects the heat exchanger 14 with a final cooler 18 for the condensate and gas. A valved conduit 15 also connects line 10 directly with the cooler through line 16. A valved conduit 20 conducts the condensate and gas from the cooler 18 to a receiver 22. Any fixed gas separating from the condensate in the receiver 22 is conducted through a conduit 24 to a fuel gas header 25 having a valve 27 and passed to storage.

The receiver 22 is also in valve-controlled communication with a flow tank 26 through the valved conduits 24 and 28. A conduit 30 having therein a pump 31 conducts liquid under pressure from the flow tank 26 through the preheaters 14 and 12 in series, and thence through a valve-controlled conduit 32 into the vertical mid-portion of a fractionating column 34 of well-known construction. Connected with the lower portion of the column 34 is an indirect heater or reboiler 36 adapted to maintain the liquid in the bottom of column 34 at a predetermined raised temperature.

A vapor line 38 leads from the top of the column 34 to a condenser and cooler 40. Liquids condensed in the condenser 40 flow therefrom through valved-controlled line 42, and may be conducted in whole or in part into the upper portion of the column 34 through the valved-controlled lines 44 and 46 by means of a reflux pump 48. A mid-portion of the condenser 40 is connected through a valved conduit 50 with the fuel gas header 25 in the manner shown.

A valve-controlled line 52 connects the reboiler 36 with the mid-portion of a second fractionating column 54 and serves for conducting partially stabilized distillate from the column 34 to column 54. Column 54 has associated with its lower portion a reboiler 56 adapted, like reboiler 36, to be heated by high pressure steam and having connections 58 and 60 for recycling the reheated liquid to the bottom of the column 54.

A vapor line 62, having therein a pressure relief valve 64, connects the top of the column 54 with a condenser 66. Condensate from 66 flows to a propane receiver 68 through a line 70, while fixed gases flow from the said condenser 66 through the valve-controlled line 72. The fixed gases from condenser 66 and receiver 68 pass to the fuel gas header 25 through the valved controlled lines 72 and 94.

The propane receiver 68 is connected with the upper portion of the column 34 by means of the valve-controlled conduits 74 and 76, branch conduits 78, and cycle-pump 80. Similarly the propane receiver 68 is in controlled communication with the upper portion of the column 54 through the conduit 74, reflux pump 82 and valve-controlled conduit 84. The said receiver 68 is also in controlled communication through conduit 74, storage pump 86 and valved conduit 88 with a propane cooler 90 and thence through line 94 with propane storage vessels 92. Propane from line 88 may be passed directly to line 70 by a valved connecting line 89.

15 A valved conduit 96 connects the reboiler 56 with the mid-portion of a third fractionating column 98. A reboiler 100 is connected with the lower portion of the stabilizing column 98, through the conduits 102 and 104, and serves for heating 20 the body of partially stabilized distillate maintained in the bottom of that column. A vapor line 106, having therein a pressure relief valve 108, connects the top of the stabilizing column 98 with a condenser 110. An outlet line 112 leads 25 from the condenser to a butane receiver 114.

The butane receiver is in controlled communication with the upper mid-portion of the fractionating column 54 through the valved lines 116, 118, cycle-pump 120, line 122 and the valve-controlled branch lines 124. Similarly, the butane receiver is in controlled communication with the upper portion of the fractionating column 98 by 30 means of the conduits 116, 130, reflux pump 132, and valved conduit 134. The receiver 114 is also in communication with butane storage tanks 135 through the lines 116, 136, storage pump 138, line 140, cooler 142 and line 144. Butane from line 140 may be passed directly to line 112 by a valved connecting line 141.

40 A conduit 162 leads from the reboiler 100 to a cooler 164, from thence the cooled and stabilized distillate is conducted through valved conduit 166 to a stabilized distillate treating plant (not shown).

45 For use in recovering propane and butane from the gases from the gathering system of the cracking units, the lower part of the receiver 22 is connected with the upper portion of an absorber column 150 of well-known construction, by means 50 of a valved line 152. The top of the absorber is connected with the fuel gas header 25 through the valved conduit 154 and conduit 24. A valve-controlled line 156 connects the bottom of the absorber 150 with the flow tank 26. Likewise a 55 gas line 158 having therein a compressor pump 160 leads to the lower portion of the absorber 150 from the gasoline run-down tanks or from a source of rich gases in the crude still receiving house.

60 In the practice of the invention in connection with the stabilization of pressure distillates from a hydrocarbon cracking operation in the apparatus of Figure 1, the vapors and fixed gases from a cracking still dephlegmator flow successively 65 through line 10, and heat exchangers 12 and 14, in each of which a considerable portion of the heat contained therein is utilized for heating unstabilized distillate flowing to the first fractionating column 34. The resultant condensate and 70 gas flow from heat exchanger 14 into the final cooler 18 where they are cooled to approximately 70° F., and in which considerable additional portions of the vapors are condensed. The mixed condensate, vapors and gases then flow into receiver 22.

The heat exchangers 12 and 14, cooler 18, and the receiver 22 are maintained at substantially the cracking still-operating pressure,—i. e. for example, approximately 235 lbs. per square inch, gauge, in order to condense all constituents condensable under these conditions and leave a substantially dry gas. The "dry" or fixed gases flow from the receiver 22 through valved conduit 23 and conduit 24 to the fuel gas header 25 past the pressure relief valve 27.

10 The distillate collected in the receiver is forced through line 152 into the top of absorber tower 150 where it flows downwardly countercurrent to a flow of rich gases being pumped into the lower portion of the absorber through line 158 15 from the crude still receiving house or from gasoline run down tanks. The thus-enriched distillate then flows to tank 26 through conduit 156.

This distillate in the flow tank 26 contains all 20 of the pentane and heavier components of the cracking still vapors and considerably more propane and butane than could be condensed from the latter at low pressures or pressures below the cracking still pressure, together with additional propane and butane recovered from the gases of 25 the gathering system.

The enriched pressure distillate is then introduced into the mid-portion of the first column 34 under a pressure very substantially greater 30 than the cracking still-operating pressure. This is accomplished by means of the pump 31 which forces the unstabilized distillate from the flow tank 26 under high pressure in series through preheaters 14 and 12, and through line 32 to the 35 column 34.

Where the maximum propane recovery is desired, a pressure of approximately 400 lbs. per square inch, absolute, at the top of column 34 is employed. The pressure at which this column is operated will be determined by the percent of 40 propane that it is desired to recover. The quantity of propane necessarily released with the methane and ethane from the first column of the stabilizing unit through line 38 decreases with 45 increased column pressure. Since the loss of propane is undesirable, the column 34 is necessarily operated at higher pressures than are usual in stabilizer operation.

The vapors and gases from the first fractionating column flow through line 38 to the condenser 40 where portions of the vapors are condensed; and all or a selected portion of such condensate is returned as reflux to the upper part 50 of the said column through the line 46.

The methane and ethane, together with the 55 small amount of propane in equilibrium therewith at the temperatures and pressure existing in condenser 40, are released as gas from the latter and pass into the fuel gas header 25. The conditions in the condenser are maintained such as to keep at a minimum the per cent of propane thus carried away with these fixed gases. These gases contain about 16% by volume of propane under the conditions of operations named, the 60 balance of the gas being methane and ethane.

65 Pressures in the column 34 and condenser 40 can be maintained quite constant by proper adjustment of the valves in conduits 42 and 50, because of the relatively large proportion of fixed 70 gases in the vapors flowing from column 34.

The pressure distillate at the bottom of column 34 is preferably maintained at a temperature not exceeding 300° F. The condensate refluxed through line 46 is in amounts and at a temperature adapted to maintain a normal operating 75

temperature of around 70° F. in the upper portion of the column 34. In addition to the heat supplied to the unstabilized distillate by the heat exchangers 12 and 14, the reboiler 36 is employed 5 to supply heat required for maintaining the desired bottom of column operating temperature. Propane recycled from the second fractionating column 54 in a manner subsequently to be described preferably is employed to assist in developing the necessary vapor pressure at the 10 bottom of column 34 at the maximum operating temperature, which is preferably of 300° F. or less.

The partially-stabilized pressure distillate or 15 liquid in the base of column 34, free from methane and ethane, is then transferred to the mid-portion of the fractionating column 54, where it is treated for the production therefrom of a fractionated propane cut which is removed 20 overhead.

The second fractionating column 54 is operated at a pressure substantially less than the operating pressure in the column 34. For example, a pressure of approximately 210 lbs. per 25 square inch, absolute, and a top-of-column temperature of 110° F. is satisfactory. The bottom-of-column temperature preferably should not exceed 300° F. A partial evaporation will result, upon the reduction of the pressure on the distillate from that of the first column to that of the lower portion of the second column.

The reboiler 56 supplies additional heat thus made necessary by revaporation at the base of the column 54 caused by this reduction of pressure. In this way, the desired temperature and reflux ratio can be maintained in the column. The pressure reducing valve 64 in the vapor line 62 leading from the second column facilitates the maintenance of a uniform temperature and pressure in this column, and makes possible the condensation of the vapors from the column 54 at a lower pressure than that in the column, so that any variation in the operating temperature of the condenser will not be reflected in the 45 operation of the column.

The overhead product removed through line 62 will be composed of propane, one portion of which will be refluxed in the column 54 for increasing therein the partial pressure of the propane. Another portion of propane will be recycled in column 34 for the purpose of increasing the mol per cent of propane in the body of hydrocarbons in the base of that column. The balance of the propane is conducted to storage.

55 The partially-stabilized pressure distillate or hydrocarbon mixture is conducted from the reboiler 56 into the lower mid-portion of the third fractionating column 98, the latter preferably being maintained at an operating pressure of approximately 60 lbs. per square inch absolute, and preferably having a bottom-of-column temperature of around 250° F. and a top-of-column temperature of around 110° F.

While the above-mentioned temperatures and 65 pressure conditions may be satisfactorily employed in the process, it will be understood that the conditions of operation of the various columns may be varied considerable and that, in the case of column 98 for instance, the vapor pressure desired for the stabilized pressure distillate or gasoline can be controlled by varying the percent of butane refluxed or by suitably varying the pressure or temperature range at which the column is operated. Under the operating conditions named above, the vapor pressure of the

average propane-free pressure distillate or gasoline may be lowered to approximately 7.6 lbs. per square inch by means of the vaporization resulting from the difference in pressure between the second and third columns and the small amount of reboiling in the third column. Increasing the pressure in the column 98 or decreasing the amount of heating in the reboiler 100 increases the vapor pressure of the stabilized product and reduces the butane yield recovered in the receiver 114; while decreasing the column pressure and increasing the reboiling at the base of the column will decrease the vapor pressure of the stabilized product and increase the butane yield. By increasing the pressure in the column 98 to 70 lbs. per square inch, a propane-free distillate having a vapor pressure of about 9 lbs. per square inch can be produced. The pressure-reducing valve 108 makes possible the maintenance of uniform conditions in the top of the column 98.

It is well known that considerable polymerization occurs when pressure distillate or gasoline is heated to high temperatures in accordance with the practice of the prior art. Such polymerization is avoided or substantially reduced in the first fractionating column 34 by refluxing condensate from condenser 40, and by recycling propane thereto from the second column receiver 68; thus increasing the vapor pressure of propane in the boiling distillate at the base of the first column and preventing a temperature rise above 300° F.

Similarly polymerization of the pressure distillate within the second column is prevented or substantially reduced by recycling butane from the third column receiver 114 and by refluxing propane drawn from receiver 68. Thus the temperatures at the base of the first and second columns are prevented from substantially exceeding 300° F. The temperature at the base of the third column will always be under 300° F., regardless of operating procedure, because of the very materially lower column pressure.

In order to strip valuable components from 45 gas gathering systems and from a crude still receiving house or gasoline down-run tanks, and to reduce the propane and butane cycle loss in the fractionating columns 34 and 54, rich gases from gathering systems are compressed and are 50 passed into the absorber 150 in intimate countercurrent contact with condensed unstabilized pressure distillate or wild gasoline, prior to pumping the same under pressure into the fractionating column 34. Only such gases as can be 55 collected with minimum air dilution (from air being drawn into tanks and lines) are suitable for this purpose. The gathered gases can not only be stripped of the pentane and heavier components, but also of a good portion of their propane and butane as well, under suitable pressure and temperature conditions.

The three-column stabilizing plant shown in Figure 1 is a flexible unit, and its operation as hereinbefore described can be controlled to produce at will, maximum or minimum yields of propane and butane and to vary the vapor pressure of the pressure distillate or gasoline as desired for the purpose of meeting seasonal requirements.

While as shown, the condensers 40, 66, and 65 110 are located latterly of the respective fractionating columns 34, 54 and 98, it is obvious that these may be in the form of reflux condensers adapted to return a selected part of the 70 75

condensate therefrom by gravity to the top of the respective fractionating columns, proportional amounts of the condensate being conducted away to storage in suitable manner.

- 5 In processing crude petroleum oil in the apparatus shown in Fig. 1, a number of fractionating stages may be used so that gasoline, kerosene, furnace oil, light lubricating stock and heavy lubricating stock may be successively removed overhead at diminishing pressures through the stages. The last stages of distillation may, if desired, be conducted under subatmospheric pressure. In many instances it may not be desirable to enrich the condensate in the receiver 22 with gases from a gathering system. In such instances the condensate is conducted from the receiver 22 through the valved lines 24 and 28 direct to the flow tank 26.
- 10 Referring to Fig. 2 of the drawings (as described in application Serial No. 195,681), the vapors to be handled in the apparatus shown therein are conducted overhead from a fractionating tower or dephlegmator 202 through a valve controlled vapor line 204. The tower 202 may 15 comprise the usual high pressure tower of a cracking unit in which a pressure of approximately 250 lbs. per square inch is maintained, or it may comprise the fractionating tower used for the fractionating of crude oil in which the gasoline hydrocarbons are separated out and removed overhead as vapors along with lower boiling hydrocarbons. In almost every conversion process where hydrocarbons are converted into gasoline motor fuel, a fractionating tower such as the tower 202 is employed for separating the pressure gasoline constituents from higher boiling hydrocarbons. In practically all of these operations the fractionation in the tower 202 is controlled so that the overhead vapor fraction 20 will have the desired end boiling point.

Assuming for example that a pressure of approximately 250 lbs. per square inch is maintained in the tower 202 from a hydrocarbon conversion operation, the vapors at approximately this pressure are conducted through the line 204 and all or a portion thereof passed by means of a line 206 through an indirect heat exchanger 208 mounted in the base of a stabilizer column 210. The vapors from the heat exchanger 208 are passed by means of a line 212 through a heat exchanger 214, and a water cooler-condenser 216 to condense all of the gasoline constituents and certain of the undesired lower boiling point hydrocarbons such as methane, ethane, propane and the propylenes. The condensate and uncondensed gases produced in this operation are conducted from the water cooler-condenser 216 through a line 218 into a high pressure receiver and vapor separator 220 where the uncondensed gases are separated from the condensate.

The pressure maintained in receiver 220 is preferably a high pressure substantially equal to that maintained in the tower 202 except for the pressure drop resulting from the vapor flow through the elements of the apparatus described. The use of high pressure in the cooling and condensing elements of the apparatus, and in the receiver 220 permits the condensation of practically all of the desired hydrocarbons as well as some undesirable constituents, so that the gases separated out in the receiver are substantially "dry." These gases are removed from the separator 220 through a line 222 which is provided with an automatic pressure controlled

valve, operated by the pressure in the receiver 220 to maintain a desired maximum back pressure. A portion of the condensate collected in the receiver 220 is preferably recycled in accordance with the usual practice as a refluxing medium to control the temperature in the top of the tower 202, the end point of the product, and maintain a desired reflux ratio in the tower. Accordingly, condensate is withdrawn from the receiver 220 through a line 224 and forced by means of a pump 226 through a line 228 into the top of the tower 202. The quantity of condensate thus introduced into the tower 202 as reflux is controlled by the pump 226 which acts by well-known means in response to a flow controller or to the variations in temperature in the top of the tower 202, as transmitted for example from a thermocouple 230, through the connecting leads 232.

The condensate produced in the above operation (that used as reflux in tower 202 is merely recycled and not deducted from the production) is withdrawn from the receiver 220 through a line 234 (which connects into the line 224), by means of an automatically controlled pump 236 and passed through a line 238 from which a portion or all of this condensate is conducted through a valved line 240 and then in indirect heat exchange with the vapors passing through the heat exchanger 214.

The flow of pressure distillate to the tower 210 may be controlled, as shown, by the float valve mechanism, or by a flow controller. Preferably the pressure distillate is supplied to the tower 210 at a substantially constant rate and the float used only as a high and low level alarm.

The preheated condensate from the exchanger 214 is conducted through lines 242 and 244 into the mid-portion of the stabilizer tower 210 for rectification. In carrying out this step of the process the proportion of condensate passed through the line 240 and heat exchanger 214 is preferably automatically controlled in accordance with the temperature at which the condensate enters the tower 210. This entrance temperature as well as the point of introduction of the pressure distillate into the tower 210 is selected to correspond with the desired temperature gradient of the tower. Therefore the temperature of the condensate entering the midportion of the tower 210 is controlled from a thermocouple 246 mounted in the line 244. This thermocouple is interconnected, by means of a connection 248, with an automatic control valve mounted in a bypass line 250 between the lines 238 and 244. The thermocouple 246, after being set to control and maintain the entrance temperature of the pressure distillate, controls the valve in the bypass 250 to regulate the amount of condensate heated in the heat exchanger 214.

The bottom temperature in the stabilizer tower 210 is preferably controlled automatically to supply the necessary heat by regulating the heating of the body of condensate in this tower by vapors from the line 204. This may be accomplished automatically in accordance with responses from a thermocouple 252 mounted in a body of liquid in the tower 210, the thermocouple being connected with a control valve mounted in a bypass line 254 between lines 204 and 212. The thermocouple 252 is set to maintain a predetermined temperature so that a slight drop in the temperature of the body of liquid in the bottom of the tower 210 will cause the thermocouple to

automatically close the valve in the bypass line 254 to increase the proportion of hot vapors passed through the tubes of heat exchanger 208. On the other hand a slight rise in temperature in the bottom of the tower 210 above the predetermined point will cause thermocouple 252 to open the valve in the bypass 254. The lines 212 and 240 near the bypasses 250 and 254 are preferably valved in order to provide a slight pressure drop in these lines, so that the automatic control will be completely effective.

The pressure distillate or other unstabilized gasoline or motor fuel material introduced into the mid-portion of the tower 210 is rectified to remove overhead the undesirable constituents which in the case of gasoline would usually include all of the propane and similar, and lower boiling constituents, as well as a part of the butane fraction. The undesirable hydrocarbons are discharged 20 overhead from the tower 210 in vapor form through a line 256, a portion thereof condensed by condenser 258, and the resulting products conducted through a line 260 into a vapor-liquid separator 262. Uncondensed gases are removed 25 from this separator through an automatic pressure valve controlled line 264. A portion of the condensate collected in receiver 262 is preferably used as reflux in the top of the tower 210 in order to control the temperature therein and the 30 initial point of the finally desired product. This condensate is withdrawn through a line 266 and forced by means of a pump 268 and a line 270 into the top of the tower 210. The amount of this condensate introduced into the tower 210 is 35 controlled to provide the desired reflux ratio by a flow controller, or by a thermocouple 272 which regulates the speed of pump 268 through a connection 274. Any excess condensate collected in the receiver 262 is withdrawn through a float 40 valve controlled line 276.

The stabilized product produced in the tower 210 is withdrawn from the bottom thereof through a float valve controlled line 278.

A high superatmospheric pressure is preferably 45 maintained in the fractionating tower 210, preferably substantially exceeding the pressure in the receiver 220. For example, in the stabilization of pressure distillates, a pressure of from 300 to 350 pounds per square inch is preferably employed in this tower. Where the process is used 50 for the stabilization of vapors derived from low pressure operations, the pressure in the receiver 220 may be approximately atmospheric, but regardless of this pressure the stabilizer tower 210 is preferably operated at a high superatmospheric 55 pressure which is derived from the pump 236. Extensive commercial operations have shown unusual advantages in carrying out the rectification in the tower 210 at pressures higher than that in the separator 220 or the fractionating tower 202.

In stabilizing a pressure distillate at a pressure of 300 lbs. in the tower 210 to produce a product having a Reid vapor pressure of nine pounds per square inch, it was necessary to maintain a bottom 65 temperature in the tower of approximately 350° F. and a top temperature of about 135° F.

The invention is obviously not limited to the treatment of distillates obtained in the pressure cracking of petroleum, but may be applied to the 70 treatment of various hydrocarbon mixtures such as wild gasoline, natural gas, and coal tar vapors for the purpose of producing a liquid hydrocarbon mixture of preselected vapor pressure and for the recovery of propane and butane. It is 75 to be understood that the terms "propane" and

"butane" as used in this specification and the accompanying claims include other hydrocarbons of similar boiling point. It is apparent that in the handling of vapors and gases from a cracking unit, that the propane and butane fractions will include olefins of similar boiling point to propane and butane.

This application contains the claims from application Serial No. 548,062 as allowed, and the claims from application Serial No. 195,681 held 10 in effect to be indivisible from certain claims of application Serial No. 584,062. Certain of the subject-matter disclosed in the latter application, and originally claimed therein, is claimed in divisional application Serial No. 104,387, filed October 7th, 1936, issued as Patent No. 2,168,316 on August 8, 1939.

Having thus described the invention, what is claimed as new is:

1. The method of stabilizing hot vapors, which 20 comprises partially cooling said hot vapors in a first cooling zone to effect condensation and separation of substantially all of the constituents heavier than those desired in the final distillate product, removing the remaining vapors and passing them first in indirect heat exchange with a distillate stock, to partially condense said vapors and heat said distillate stock, then in indirect heat exchange with another cooling medium to cause the final desired degree of condensation of the vapors, whereby substantially all of the constituents thereof desired in the final product are 30 condensed, with some undesired constituents, collecting resulting condensate and removing incondensable gases therefrom, passing condensate so obtained in indirect heat exchange with said hot vapors, as said distillate stock, whereby said hot vapors are initially cooled and said condensate is heated, introducing resulting heated condensate into an intermediate point in a stabilizing 40 column under substantially superatmospheric pressure wherein undesired excessively volatile constituents are separated as vapors from said desired constituents as liquids, removing said undesired excessively volatile constituents from the 45 top of said column, withdrawing the stabilized product from the base of said column and applying additional heat from an external source to the base of said column.

2. The process of fractionating hot vapors removed from a distilling operation, which 50 comprises passing them first in indirect heat exchange with a distillate stock to partially condense said vapors and heat said distillate stock, then in indirect heat exchange with another cooling medium to cause the final desired degree of condensation of the vapors whereby substantially all of the constituents thereof desired in the final product are 55 condensed with some constituents undesired in the final product, collecting the resulting condensate and removing any uncondensable gases therefrom, passing condensate so obtained in indirect heat exchange with said hot vapors as said distillate stock, whereby said hot vapors are initially cooled and said condensate is heated, introducing resulting heated condensate into an intermediate point in a fractionating 60 column wherein excessively volatile constituents undesired in the final product are separated as vapors, removing said undesired excessively volatile constituents from the upper part of said column, and withdrawing the resulting product from the base of said column.

3. The process of fractionating hot oil vapors removed from a distilling operation, which 70 com-

prises passing them in indirect heat exchange with a relatively cool distillate stock to cool the vapors, condensing substantially all of the constituents of said vapors desired in the final product together with some constituents undesired in the final product, collecting the resulting condensate and passing it through an absorbing zone in intimate contact with a mixture of hydrocarbon gases containing desirable and undesirable constituents to absorb desirable constituents from said gases, passing said condensate containing absorbed constituents from said absorption zone in indirect heat exchange with said hot vapors as said distillate stock whereby said hot vapors are cooled and said condensate is heated, introducing the resulting heated condensate containing absorbed constituents into a fractionating column wherein undesirable excessively volatile constituents are separated by fractionation and removed overhead from the column, and withdrawing the resulting product from the base of the column.

4. The process of fractionating hot oil vapors as defined by claim 3 in which said hot oil vapors are produced in a hydrocarbon cracking operation and in which a substantially greater pressure is maintained in said fractionating column for the elimination of said excessively volatile constituents than the pressure maintained on said hot oil vapors while they are being condensed.

5. The process of fractionating hot oil vapors as defined by claim 3 in which said hot oil vapors are produced by a hydrocarbon cracking operation and include constituents within the gasoline range, and in which said resulting product withdrawn from said base of said fractionating column is further fractionated to recover a condensate of lower boiling point than gasoline which is relatively free of said excessively volatile constituents.

6. In the fractionation of hot oil vapors produced in a distilling operation, the improvement which comprises passing said hot oil vapors in indirect heat exchange with a relatively cool distillate stock to cool the vapors and heat the distillate stock, condensing substantially all of the readily condensable constituents of said vapors, collecting the resulting condensate and separating it from any uncondensable gases, passing said condensate in indirect heat exchange with said hot oil vapors as said distillate stock whereby said hot vapors are cooled and said condensate as said distillate stock is heated, passing the resulting heated condensate into a fractionating column and therein subjecting it to fractionation to separate out undesired excessively volatile constituents which are removed overhead from the column, and withdrawing the remainder of the condensate free of said excessively volatile constituents from the base of the column.

7. In the fractionation of hot oil vapors as defined by claim 6 in which said hot oil vapors are produced in a hydrocarbon cracking operation and in which a substantially greater pressure is maintained in said fractionating column for the elimination of said excessively volatile constituents than the pressure maintained on said hot oil vapors while they are being condensed.

8. In the fractionation of hot oil vapors as defined by claim 6 in which said hot oil vapors are produced by a hydrocarbon cracking operation and include constituents within the gasoline range, and in which said resulting product withdrawn from said base of said fractionating column is further fractionated to recover a condensate of lower boiling point than gasoline which is rela-

tively free of said excessively volatile constituents.

9. In the production of a stabilized gasoline from a mixture of products produced in a hydrocarbon cracking operation carried out at a high superatmospheric pressure, the improvement in the handling of the cracked vapor products which comprises conducting the mixture of hot cracked vapor products containing gasoline constituents, lower boiling hydrocarbons, and uncondensable gases through a condensing zone and condensing the said vapors at a high superatmospheric pressure adapted to condense substantially all of the hydrocarbons of higher molecular weight than ethane, conducting the resulting condensate and uncondensed gases into a receiver maintained at approximately the pressure in said condensing zone and therein separating the resulting condensate mixture from relatively dry uncondensed gases, discharging the separated gases from the receiver, passing the separated condensate containing gasoline constituents, lower boiling hydrocarbons and absorbed excessively volatile relatively dry gaseous constituents from said receiver in indirect heat exchange with the hot vapors in said condensing zone to cool said vapors and heat said condensate, thereafter introducing the heated condensate into a fractionating tower maintained at a substantially greater pressure than that maintained in said receiver and therein subjecting the condensate to rectification to remove therefrom gases having a molecular weight lower than that of propane, and fractionating the remainder of the cracked products to separate out a condensate fraction of lower boiling point than gasoline and a separate fraction containing the desired gasoline constituents.

10. The improvements as defined by claim 9 in which condensate collected in said receiver is passed into the upper portion of an absorbing tower and passed downwardly therethrough in countercurrent intimate contact with rich hydrocarbon gases, and thereafter passing the resulting enriched condensate in said heat exchange and then into said fractionating tower.

11. In the process of producing a stabilized gasoline from the vapor products produced in a hydrocarbon cracking operation, the improvement which comprises condensing the cracked vapor products containing constituents boiling in the gasoline range in a condensing zone maintained under a superatmospheric pressure to produce an unstable condensate mixture containing gasoline, collecting the resulting condensate in a receiving zone, passing condensate from said receiving zone into the upper part of an absorption column and passing it downwardly therethrough in intimate contact and countercurrent with rich hydrocarbon gases, passing the resulting enriched condensate from said absorption column in indirect heat exchange with the vapors being condensed in said condensing zone to cool said vapors and heat said enriched condensate and thereafter introducing said heated enriched condensate into a fractionating column wherein undesired excessively volatile constituents are separated by fractionation and removed overhead from the column, maintaining a greater superatmospheric pressure in said fractionating column than that maintained in said condensing zone and withdrawing the resulting condensate product free of said undesired excessively volatile constituents from the base of said fractionating column.

12. In the process of stabilizing gasoline in which the gasoline constituents to be stabilized, together with lower boiling point hydrocarbons,

- are removed in vapor form from a high temperature dephlegmator, condensed, and the resulting condensate then stabilized in a fractionating tower, the improvement which comprises passing vapors removed from said dephlegmator in indirect heat exchange with a body of liquid gasoline material in the base of said tower, the vapors passed in said heat exchange being sufficient to maintain the desired temperature at the base of said tower, passing all of the vapors removed from said dephlegmator including those passed in said heat exchange through a heat exchanger and a condenser to cool the vapors and condense the gasoline constituents and some of said lower boiling hydrocarbons, separating the resulting condensate from the uncondensed hydrocarbons in a separating zone, passing resulting condensate from said separating zone at a pressure higher than that maintained in said separating zone into the mid-portion of said fractionating tower, conducting a sufficient portion of the condensate passed to said tower in indirect heat exchange with vapors in said heat exchanger to bring the entire condensate passed to the mid-portion of said tower to a predetermined desired temperature, and stabilizing the condensate introduced to said tower to eliminate therefrom undesired low boiling point constituents.
13. The process of stabilizing gasoline as defined by claim 12 in which the quantity of vapors passed in indirect heat exchange with the body of gasoline in the bottom of said tower is automatically controlled in accordance with the temperature of said body.
14. The process of stabilizing gasoline as defined by claim 12 in which the condensate passed from said separating zone through said heat exchanger prior to its introduction into the mid-portion of said tower, and in which the quantity of condensate passed through said heat exchanger is controlled in accordance with the temperature of said mixture prior to its introduction into the mid-portion of said tower.
15. In the process of stabilizing gasoline in which the gasoline constituents to be stabilized, together with lower boiling point hydrocarbons are removed in vapor form from a high temperature dephlegmator, condensed and the resulting condensate then stabilized under rectifying conditions in a fractionating tower, the improvement which comprises passing vapors from said dephlegmator in indirect heat exchange with a body of liquid gasoline in the bottom of said fractionating tower to maintain the desired temperature for the rectification of the unstable gasoline introduced into said tower, thereafter pass-

ing the vapors from said heat exchange through a heat exchanger and a condenser to further cool the vapors and condense the gasoline constituents and some of said lower boiling point hydrocarbons, separating the resulting condensate from uncondensed hydrocarbons in a separating zone, passing separated condensate from said zone in indirect heat exchange with the vapors passing through said heat exchanger to heat the condensate to a predetermined temperature and then introducing the resulting heated condensate into the mid-portion of said fractionating tower, and rectifying the condensate introduced into said tower to stabilize the same and eliminate undesirable low boiling point hydrocarbons.

16. In the production of a rectified product having a predetermined boiling range from a vapor mixture containing the constituents of said product and lower boiling point constituents, in which the vapor mixture is condensed and the resulting condensate fractionated under rectifying conditions in a fractionating tower, the improvement which comprises passing the vapor mixture at a relatively high temperature in indirect heat exchange with a body of rectified product in the bottom of said fractionating tower to maintain the desired temperature therein, thereafter passing the vapors through a cooling zone to further cool the vapors and condense the constituents of said product as well as some of said lower boiling point constituents, separating the resulting condensate from any uncondensed vapors in a separating zone, passing separated condensate from said separating zone in indirect heat exchange with the vapors passing through said cooling zone to heat the condensate to a predetermined temperature and then passing the resulting heated condensate into the mid-portion of said fractionating tower, and rectifying the condensate introduced into said tower to produce said rectified product having said predetermined boiling range and eliminate constituents of lower boiling point.

17. The process defined by claim 16 in which said vapors are condensed at a substantially high superatmospheric pressure and in which said rectification is carried out at a pressure higher than that used in said condensation.

18. The process defined by claim 16 in which the temperature of the condensate introduced into the mid-portion of said fractionating tower is controlled by regulating the proportion of said condensate passed through said cooling zone and heated by the indirect heat exchange with hot vapors passed therethrough.

DAVID G. BRANDT.
